UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

STRETCHING DEVICE FOR IRONING-BOARDS.

1,085,525.

Specification of Letters Patent.

Patented Jan. 27, 1914.

Application filed April 28, 1913. Serial No. 764,201.

To all whom it may concern:

Be it known that I, WILLIAM BARTHOLOMEW, a citizen of the United States, residing at Chicago, in the county of Cook and State of Illinois, have invented certain new and useful Improvements in Stretching Devices for Ironing-Boards, of which the following is a specification, reference being had therein to the accompanying drawings.

10 This invention relates to certain new and useful improvements in tail stretchers for ironing boards and more particularly to an improvement upon my application for patent for bosom board, filed June 15, 1910, 15 Serial Number 567,026; the object being to provide a bosom board with a tail stretcher formed of a pair of stretcher bars, each extending beyond the longitudinal center of the board in order that the tails of a shirt 20 having overlapping portions can be evenly stretched upon the board.

Another object of the invention is to provide a stretcher which is formed of a fixed revolvably mounted stretcher bar section and 25 a movably revolvably mounted stretcher bar section, whereby the tension on the overlapping tail of the shirt can be increased by swinging the bar downwardly.

Another object of the invention is to provide a tail stretcher which is so constructed that the same can be easily and quickly placed in position upon any form of ironing board; means being provided for holding the revoluble stretcher bars in adjusted position to hold the article in stretched position upon the board.

Other and further objects and advantages of the invention will be hereinafter set forth and the novel features thereof defined by the 40 appended claims.

In the drawings—Figure 1, is a top plan of a bosom board showing the application of my improved construction of tail stretcher thereto; Fig. 2, is a perspective of my improved tail stretcher showing the same in position upon a board which is shown in dotted lines; and Fig. 3, is a longitudinal section through a portion of one of the arms showing the ratchet mechanism and pawl for holding the stretcher bar in its adjusted position.

Like numerals of reference refer to like parts in the several figures of the drawings.

In the drawings, 1 indicates an ironing

board having at one end, a neck band clamp 55 2 and a clothing clamp 3 constructed substantially the same as disclosed in my former application and these clamps are adapted to engage the shirt and securely clamp the same in position upon the board at that end; a 60 detailed description of the above-mentioned parts being unnecessary as the construction is clearly shown in my former application and forms no part of this invention, except to provide means for clamping an article 65 at one end of the board, as various other constructions of clamping means can be employed in connection with my improved construction of tail stretcher which will be 70 hereinafter fully described.

My improved construction of tail stretcher comprises a pair of revolvably mounted stretcher bar sections 4 and 5 arranged at the opposite end of the board 1 as clearly shown in Fig. 2 and these sections are of 75 such length that they extend to each side of the longitudinal center of the board in order to accommodate the overlapping portions of the tail of a shirt when placed in position upon the board. The stretcher bar sections 80 4 and 5 are carried by tubes 6 which are mounted upon shafts 7 journaled in suitable bearings carried respectively by the arms 8, 8' and 9, 9', and each tube 6 is provided at one end with a ratchet 10 inclosed 85 in a protecting casing 11. For the purpose of retaining the ratchets 10 and the roll sections carried thereby in their adjusted positions, I provide a spring-actuated sliding pawl 12 which can be thrown out of engagement with the ratchet by operating the loop trigger lever 13.

The construction of ratchet mechanism, sliding pawl and roller or stretcher bar mounting is substantially the same as disclosed in my former application and a detailed description of each of the same is unnecessary, as each of these stretcher bars is mounted upon a shaft to rotate in order to allow the tail of a shirt to be wound thereon, 95 100 and while I have only shown a ratchet mechanism for one of these bars, it is of course understood that the other stretcher bar is provided with a similar construction and that by referring to the former application, 105 the manner of mounting the same can be clearly understood.

The arms 8 and 8' are secured to the

under side of the bosom board by fastening means as shown and extend outwardly therefrom in a plane slightly below the surface of the board and at such a distance that the operator can readily grasp the tail of a shirt and manually operate the stretcher bar section so as to wind the same thereon in order to stretch the shirt being ironed upon the board.

10 The arms 9 and 9' are pivotally mounted as shown at 14 in brackets 15 secured to the under side of the board by suitable fastening means, as clearly shown, in order to allow the stretcher bar section 5 to be lowered and it will be noted that the arm 9' is curved in order to bring the bearing for the stretcher bar upwardly into substantially the same horizontal plane as the stretcher bar 4; the arms 9 and 9' being of greater length 15 than the arms 8 and 8', so as to allow the manipulation of the stretcher bars independently.

15 In the operation of my improved tail stretcher in connection with a board as described, a shirt or the article to be pressed is placed upon the board and the same is then clamped by the neck band and yoke clamps and the tails of the shirt are wound upon the stretcher bar sections 4 and 5; the 20 bar 4 being first manipulated in order to stretch the under tail section of the shirt first and the bar 5 is then manipulated so as to stretch the upper or overlapping tail section and by swinging the arms downwardly, the 25 tension can be increased so as to remove all wrinkles and stretch the same upon the bosom board in such a manner that the overlapping tail sections when being ironed, will be held in their proper positions whereby a 30 great deal of time and expense is saved in ironing what is known in the trade, as a coat shirt.

35 In my former application, the stretcher bar sections did not extend to each side of the longitudinal center of the board and the above construction is advantageous in ironing various forms of wearing apparel, where it is desired to iron the overlapping portions thereof, as with this construction 40 they can be overlapped and held in proper position when being ironed.

I claim:

1. In an ironing board, supporting arms at one end thereof, independently rotatable 45 stretcher bars revolvably mounted in said arms, said bars extending inwardly from opposite sides beyond the longitudinal center of the board and terminating short of the opposite side thereof.
2. In an ironing board, companion pairs 50 of arms arranged at one end thereof, one pair being fixed and the other movable, and stretcher bars carried by said pairs of arms.
3. In a bosom board, stretcher bar sections 55 arranged at one end thereof extending in-

wardly from opposite sides to each side of the longitudinal center of the board, means for holding said stretcher bar sections in their adjusted position, one stretcher bar being movably mounted in respect to the 70 other stretcher bar.

4. The combination with a bosom board, of stretching means disposed transversely at one end thereof comprising independently rotatable sections, said sections extending inwardly from opposite sides beyond the longitudinal center of said board and terminating short of the opposite side thereof. 75

5. The combination with a bosom board, of clamping means for retaining an article at one end thereof, stretching means disposed transversely at the opposite end and comprising independently rotatable sections, said sections extending inwardly from opposite sides beyond the longitudinal center of 80 said board, and means for retaining an article in stretched position upon said board. 85

6. A bosom board having independently rotatable stretcher bar sections at one end thereof, one section being fixed in respect 90 to said board and the other section being mounted to move in respect thereto, and means for holding said stretcher bar sections in their adjusted positions.

7. The combination with a bosom board, of means for holding an article upon said board at one end thereof, stretching means disposed transversely at the opposite end and comprising revoluble stretcher bars arranged transversely of said board and extending inwardly from opposite sides beyond the longitudinal center thereof, and means for holding said stretcher bars in 95 adjusted position. 100

8. The combination with a bosom board, of stretching means disposed at one end thereof comprising independently rotatable sections arranged transversely thereof and extending inwardly from opposite sides beyond the longitudinal center of said board, and terminating short of the opposite side 105 thereof. 110

9. The combination with a bosom board, of a pair of arms fixed at one end thereof, a stretcher bar mounted in said arms, a second 115 pair of arms movably mounted upon said board, a stretcher bar carried by said arms, said bars extending inwardly from opposite sides beyond the longitudinal center of said board, and means for holding said stretcher 120 bars in adjusted position.

10. The combination with a bosom board, of a fixed pair of arms extending from one end thereof, a stretcher bar carried by said arms, a pair of brackets fixed to said board, a second pair of arms pivotally mounted in said brackets, a stretcher bar carried by said last-mentioned arms and extending beyond the first-mentioned stretcher bar, said 125 stretcher bars extending transversely from 130

opposite sides to each side of the longitudinal center of said board.

11. In an ironing board, stretching means disposed at one end thereof comprising independently rotatable overlapping stretcher bars, and means for holding said bars in adjusted position.

12. In an ironing board, stretching means disposed at one end thereof comprising inde-

pendently rotatable overlapping stretching bars, one of said bars being movably mounted in respect to the other bar.

In testimony whereof I affix my signature in presence of two witnesses.

WILLIAM BARTHOLOMEW.
